Design No. 12,109, dated January 11, 1881.

THE
N. C. Wedder Pattern Works
Troy N.Y.

UNITED STATES PATENT OFFICE.

H. CLAY BASCOM AND CYRUS A. HODGES, OF TROY, AND TOBIAS S. HEISTER,
OF LANSINGBURG, ASSIGNORS TO THE N. S. VEDDER PATTERN WORKS,
BASCOM, GALBRAITH & CO., OF TROY, NEW YORK.

DESIGN FOR A STOVE.

SPECIFICATION forming part of Design No. 12,109, dated January 11, 1881.

Application filed November 24, 1880. Term of patent 3½ years.

To all whom it may concern:

Be it known that we, H. CLAY BASCOM and CYRUS A. HODGES, of the city of Troy, in the county of Rensselaer and State of New York, and TOBIAS S. HEISTER, of the village of Lansingburg, in said county and State, have jointly invented and produced a new and original Design for Base-Burning Stoves, of which the following is a specification, reference 5 being had to the accompanying print, cut, or engraving of a stove having our said new design.

The design for the urn consists of the inverted-pear-form ornamented body *a* and the 15 ornamented horseshoe-form crest *b*, having the ornamented top-extension *c*, with a representation thereon of a spired church, *d*, all shaped, ornamented, and arranged in combination so as to present the appearance represented in 20 the accompanying cut.

The design for the panel ornament *B* consists of the representation of a spired church, *e*, with the ornamental foreground *f* and trees *g* in the background, surrounded by a frame-like border, *h*, all shaped, positioned, and combined so as to appear as represented in the accompanying engraving.

The design for the upper section, *C*, consists of the panel ornaments *B*, composed as 30 above specified, on panels separated by the ornamented pilaster *D*, and having the series of three-lobed ornaments *i i* along the tops and bottoms of the panels, all being shaped and arranged together as shown in the accompanying print.

The design for the upper mica-light section consists of the convexly-curved frames *E*, each having the lower row of two lights, *F F*, each with the bottom *j* and sides *k* straight, 40 and the top composed of three concave arcs, *l m l*, forming two downwardly-pointing angles, *n n*, as shown, in combination with the upper row of three smaller lights, *G H G*, having straight tops *o* and sides *p* and truncate 45 upper corners, *q*, and bottoms conformed to the tops of the lower lights, *F F*, whereby the middle one, *H*, of the upper lights has a concave bottom, *r*, with angular ends, and the two side lights, *G G*, each have the outer part,

50 of the bottom depressed and the inner part, *t*, longer and convexly curved upward, and forming an obtuse angle with the part *s*, all being shaped, proportioned, and combined as shown in the aforesaid engraving.

The design for the side plates, *I*, of the rear 55 draft-flue section consists of the middle lyre-form ornament, *J*, and top and bottom ornaments, *K*, all shaped and arranged together as shown in the aforesaid cut.

The design for the ash-pit section consists of 60 the vertically-concave portion *M*, having thereon the lower net-work ornamentation, *u*, the top ornamentation, *u'*, and the intermediate lyre-form ornaments *v* and branched ornaments *v'*, all shaped and arranged together 65 as shown in the aforesaid print.

The design for the base *N* consists of the series of alternate ornaments *w w'* on the convex molding *x*, and the border *O*, having linear 70 incuts *y*, and the lower edge, *z*, formed with convex and concave curves and intermediate angles and straight parts, all shaped and arranged together as shown in the aforesaid engraving.

The design for the legs consists of the triangular downwardly-pointing ornament *P*, having 75 therein the angular bar *P'*, and the compound pendent ornament *Q*, having the circular or oval upper part and hanging stem, with lateral ornaments disposed on the swelling surface 80 *R*, having the side scrolls, *S*, all shaped and arranged together as shown in the aforesaid cut.

What we claim as our invention is—

1. The design for the urn, composed of the parts *a b c d*, all shaped and combined as set forth.
2. The design for the panel ornament *B*, composed of the parts *e f g h*, all shaped, placed, and combined as set forth.
3. The design for the upper section, *C*, consisting of the parts *B D i i*, all shaped, composed, and arranged together as set forth.
4. The design for the upper mica-light section, composed of the frames *E*, each embracing the lower row of two lights, *F F*, having 90 their edges *j k l m l n n* shaped as shown and described, in combination with the upper row of three differing lights, *G H G*, having the 95

respective edges *o p q r s t* thereof all shaped as shown and described.

5. The design for the side plates, *I*, of the rear draft-flue portion, consisting of the ornaments *J K*, all shaped and combined as set forth.

6. The design for the ash-pit section, composed of the parts *M u u' v v'*, all shaped and combined as set forth.

10 7. The design for the base *N*, composed of the parts *w w' x* and *O y z*, all shaped and arranged as set forth.

8. The design for the legs, consisting of the parts *P P' Q R S*, all shaped and combined as set forth.

15 In testimony whereof we hereunto set our hands, in the presence of two subscribing witnesses, this 22d day of November, 1880.

H. CLAY BASCOM.

CYRUS A. HODGES.

TOBIAS S. HEISTER.
